Inventor
Thomas G. Hitt

Wm. Fenwick Farnsworth,
Attorneys

UNITED STATES PATENT OFFICE.

THOMAS G. HITT, OF SEATTLE, WASHINGTON.

FIRECRACKER.

Application filed March 12, 1926. Serial No. 94,247.

This invention relates to improvements in the construction of fire crackers, particularly in the means for retaining the explosive substance.

5 The prime object of this invention is to provide a receptacle for the explosive material which would be adapted to receive the explosive substance in such a manner that the explosive material will be held within 10 the receptacle at one end by a sealing element in the form of finely powdered compact sealing wax or other suitable substance at the other end by a bent over portion of the receptacle, the end of the fuse contacting 15 with the explosive substance also being adapted to be held in position by means of the bend. The bent receptacle being positioned within the fire cracker container at a suitable point between its ends.

20 Another object of this invention is to provide an improved fire cracker of a simplified construction particularly in the means for inserting the explosive material and in the means for retaining the explosive material 25 within the receptacle.

Further objects of this invention appear in the following detailed description of the fire cracker, and in the disclosure as shown in the single sheet of drawings which is 30 herewith made a part of this application.

In the drawing,

Fig. 1 illustrates a sectional vertical view of the fire cracker showing the explosive receptacle in assembled relationship to the 35 fire cracker container.

Fig. 2 represents a side vertical view of the fuse and explosive receptacle in folded or bent form for insertion in the fire cracker container.

40 Fig. 3 illustrates a side vertical view in section of Fig. 2 to an enlarged scale showing the means for retaining the explosive material in place within the receptacle.

Numeral 1 designates the container for a 45 fire cracker made of any suitable material and adapted to receive a receptacle 2, which is designed to receive the explosive material 3 and the fuse 4.

The receptacle 2 in this invention is bent 50 at a desired point 5, forming an angle having 2 leg portions 6 and 7, the leg portion 7 being adapted to receive or hold the explosive material 3 which may be inserted into the receptacle through the open end 8 of the leg portion 7. After the insertion of

the explosive material, a sealing element 9 is located within the open end 8 thereby effectively closing the open end of the explosive receptacle which consists of one leg portion 7 of the receptacle 2. The explosive material 3 having been inserted in the receptacle leg 7, is firmly held in place at its inner end by the bend 5 of the receptacle 2. The fuse 4 may be of a looped or other suitable type, the end contacting with the explosive substance 3 being adapted to be held firmly in place by means of not only the explosive material, but also the bend 5. The fuse 4 will be passed through the leg portion 6 of the receptacle 2 around the bend 5 into the 70 explosive material 3.

This invention provides a fire cracker having a simplified construction and at the same time increasing its explosive powers or report. The receptacle may be of any 75 desired shape, circular, oblong, or other tubular forms may be used. The sealing substance 9 may be composed of wax or other material suitable for the purpose, particularly a type of material which will tend, 80 on the explosion of the fire cracker, to sift into a fine powdered form.

It may be readily observed that the construction of this fire cracker has been greatly simplified over those now in public use, in that the explosive material is held in but one portion of the receptacle, while but one end of the receptacle is required to be sealed, that is, the explosive material is held firmly within the receptacle at one end by a bend 90 in the receptacle and at the other end by the insertion of a sealing element adapted to sift into fine particles on the explosion of the fire cracker, the fuse meanwhile also being firmly held in place by the bend in 95 the receptacle. Obviously, the receptacle together with its fuse and explosive material, may be inserted within the container of the fire cracker in the usual manner, the legs of the bent receptacle tending to spring 100 outwardly and thereby insuring a firm contact with the walls of the container.

It is to be understood that the disclosure in this application, covers one embodiment 105 to this invention. Other embodiments of the invention may consist of various forms and shapes of fire crackers or explosives and a multiplicity of bends in the receptacle for the explosive material.

Various changes, variations, substitutions 110

and modifications may, therefore, be resorted to without departing from the spirit and scope of this invention.

What I claim is:

- 5 1. A fire cracker comprising a container, a receptacle for an explosive material within and between the ends of the container, the receptacle being bent at an angle, one of the leg portions of the angle being adapted to receive a fuse and the other leg portion forming a chamber for the explosive material, a suitable sealing composition in the open end of the chamber for holding the explosive material in place, the inside end portion of the explosive material, and

and the inside end section of the fuse being held firmly in place by the bend.

2. A fire cracker having a fuse, comprising a container, a bent receptacle for an explosive material within and between the ends of this container, means for firmly holding the receptacle against the walls of the container, consisting of the pressure due to the bent receptacle, means for holding the explosive material consisting of one arm portion of the bent receptacle, another arm portion being adapted to receive the fuse.

In testimony whereof I affix my signature.

THOMAS G. HITT.
